UNITED STATES PATENT OFFICE.

KARL GARNER, OF ST. MARYS, PENNSYLVANIA.

FOLDING SCAFFOLD-BRACKET.

1,347,453.

Specification of Letters Patent.

Patented July 20, 1920.

Application filed September 8, 1919. Serial No. 322,334.

To all whom it may concern:

Be it known that I, KARL GARNER, a citizen of the United States, residing at St. Marys, in the county of Elk and State of Pennsylvania, have invented certain new and useful Improvements in Folding Scaffold-Brackets; and I do declare the following to be a full, clear, and exact description of the invention, such as will enable others skilled in the art to which it appertains to make and use the same.

This invention relates generally to painters' equipment, but more particularly to scaffold brackets.

15 The principal object of the invention is to provide a prop scaffold bracket which is collapsible or foldable so that when it is not in use it may be folded into a comparatively compact article and be easily transported.

20 The bracket includes a supporting prop which is adjustable longitudinally so that the scaffold may be adjusted to different heights.

Another object of the invention is to provide a device of this class which will be extremely simple, strong, durable and inexpensive in construction, one which will be efficient and reliable in operation, and well adapted to the purpose for which it is designed.

With these and other objects in view, the invention consists of certain novel features of construction, and the combination and arrangement of parts as will be hereinafter 35 fully described and claimed.

In the accompanying drawings, in which similar reference characters designate like parts throughout the several views,

Figure 1 is a side elevation of a bracket 40 constructed in accordance with this invention, showing it in operative position against a wall;

Fig. 2 is an edge view of the bracket in the position in Fig. 1; and,

45 Fig. 3 is a side elevation of the bracket showing it in folded position.

Referring more particularly to the drawings, the numeral 1 designates an upright bar adapted to rest against a wall or other 50 upright support. The bar 1 is composed of a pair of angle bars 2 arranged back to back but in a slightly spaced relation. The upper ends of the angle bars 2 are riveted or otherwise secured to a triangular plate 3,

the angle bars 2 being disposed on opposite 55 sides of the plate 3 and extending along one of the right angular edges of the same.

Pivoted to the corner of the plate 3 remote from those occupied by the angle bars 2 is a supporting bar or arm 4 which like the bar 60 1 is made up of a pair of angle bars 5 arranged back to back and having their adjacent sides disposed in a slightly spaced relation so that the pivoted ends of the angle bars are disposed on opposite sides of the 65 plate 3.

Pivoted at one end between the vertical and spaced flanges of the angle bars 5 and adjacent the free or outer ends of the same is a brace bar 6. This brace bar 6 is arranged diagonally, slanting toward the bar 1 and has its other end disposed between the lower ends of the adjacent flanges of the angle bars 2 and secured thereto by means of a removable pin 7, which extends through 70 the openings 8 in the angle bars 2 and an opening 7 in the brace 6. The brace 6 has riveted or otherwise securely fastened to its intermediate portion a hook-shaped keeper 75 10, the open end of which is disposed toward 80 the bar 1.

Pivoted at its upper end to the plate 3 and crossing the diagonal brace 6 is a diagonal prop 11 which fits into the keeper 10 and which is provided with a sharpened lower 85 end adapted to embed into the ground or other support upon which the prop is placed. The prop 11 is preferably composed of an upper section 12 and a lower section 13 into which the upper section slides or telescopes. 90 When the two sections 12 and 13 are adjusted with respect to each other, a pin 14 is placed through one of the series of holes 15 in the lower section 13 and the upper section 12 rests upon this pin and prevents the collapsing of the two sections. 95

In constructing a scaffold two or more of the improved brackets are used. Each of the brackets used is extended and set up in the manner shown in Fig. 1 of the drawings, the bar 1 resting against the upright wall W, the prop 11 embedded in and resting upon the ground or floor G, the brace 6 secured at its lower end to the bar 1 by means of the pin 7, and with the hook 10 100 105 engaging around and resting upon the adjacent portion of the prop 11. The arm 4 will thus be maintained in a horizontal po-

sition so that a number of planks forming the platform of the scaffold may be supported by the arm.

At any time it is desired to raise or lower the scaffold it is only necessary to remove the pin 14 and allow the sections 12 and 13 to telescope and then place the pin back into the proper opening. Every time the height of the scaffold is changed the distance of the lower end of the prop from the vertical wall W must be changed so that the prop will be brought to bear against the keeper 10.

The bracket can be collapsed or folded by removing the pin 7, and swinging the prop 11 and arm 4 with the brace 6 in longitudinal alinement therewith into parallel relation with the bar 1. The compact article thus formed can be easily transported.

From the foregoing description taken in connection with the accompanying drawings, the construction, use and operation of the device will be readily understood.

As various changes in form, proportion, and in the minor details of construction may be resorted to without departing from the spirit of this invention it is to be understood that I do not wish to be limited to the exact construction herein shown and described.

What is claimed is:

1. A device of the class described comprising a plate, an upright bar secured at its upper end to said plate, a horizontal supporting arm pivoted at one end to said

plate, a diagonal brace pivoted at one end to the other end of said arm, means for detachably connecting the lower end of said brace to the lower end of said bar, a diagonal prop pivoted at its upper end to said plate and crossing said brace at the intermediate portion of the same, and a hook-shaped keeper secured to the intermediate portion of said brace and adapted to be hooked around said prop. 40

2. A device of the class described comprising a triangular shaped plate, a pair of upright angle bars arranged back to back in slightly spaced relation on opposite sides of said plate and secured at their upper ends to the same, another pair of angle bars arranged back to back in slightly spaced relation and having one of their ends disposed on opposite sides of said plate and pivotally connected thereto, a diagonal brace bar having one end disposed between the adjacent flanges of the last named angle bars and its other end removably secured between the adjacent flanges of the first named angle bars, a diagonal prop pivoted at its upper end to said plate and crossing said brace bar at substantially the intermediate portion of the same, and a hook-shaped keeper secured to the intermediate portion of said brace bar and 55 adapted to engage said prop. 60

In testimony whereof I have hereunto set my hand.

KARL GARNER:
